CLAIM

The ornamental design for a static mixer, as shown and described.

DESCRIPTION

FIG. 1 is a front perspective view of the static mixer;
FIG. 2 is a back perspective view of the static mixer;
FIG. 3 is a front elevational view thereof;
FIG. 4 is a side elevational view thereof; and,
FIG. 5 is a side cross-sectional view of the static mixer used
at the output of a venturi device within an output tube, with
the venturi device and the output tube shown in broken lines
for environment and form no part of the claimed design.
